US0D1018025S

(12) United States Design Patent (10) Patent No.: US D1,018,025 S
(45) Date of Patent: * Mar. 19, 2024

(54) BACKPACK

(71) Applicant: DECATHLON, Villeneuve d'Ascq (FR)

(72) Inventor: Malo Sahores, Villeneuve d'Ascq (FR)

(73) Assignee: DECATHLON, Villeneuve d'Ascq (FR)

() Term: 15 Years

(21) Appl. No.: 29/836,212

(22) Filed: Apr. 25, 2022

(30) Foreign Application Priority Data

Oct. 29, 2021 (EM) 008741532-0001

(51) LOC (14) Cl. 03-01

(52) U.S. Cl.

USPC D3/216; D3/217

(58) Field of Classification Search

USPC D3/215-218, 225, 226, 230-232, D3/252-254, 262, 285-289, 303, 321, D3/327
